UNITED STATES PATENT OFFICE.

JOHN THOMSON HAYWARD, OF PLOESTI, RUMANIA.

ROTARY WELL-DRILLING MACHINERY.

Application filed May 18, 1923. Serial No. 639,928.

The present invention has reference to improvements in rotary well drilling machinery and more particularly to apparatus for automatically feeding down the bit and for maintaining practically constant couple (torque) in the drill stem.

As ordinarily carried out, the feeding down of the bit is done by the driller, who varies the pressure on the brake so as to allow the drill to fall. However, he has no direct means of estimating the resistance offered to the bit, and consequently of the couple that is being applied to the drill stem. If he feeds too rapidly a twist off may result, while if he is careful the rate of advance is liable to be below the maximum possible with the drill stem used.

The present invention, as described below, concerns apparatus which regulates the feed so that a constant and predetermined couple is maintained in the drill stem and which indicates this couple for the driller's information. The operation of the apparatus is based upon the fact that in a steam driven rotary rig the couple in the drill stem is directly proportional to the mean effective pressure in the engine cylinder. This M. E. P. is of course, when the rig is running normally with the throttle partly open, something less than the boiler pressure due to the wire-drawing or throttling effect of the throttle valve.

The accompanying drawing Figure 1 shows a diagrammatic plan view of one method of carrying out the invention, and Fig. 2 is a diagrammatic plan showing the line shaft and drum connected to the well known rotary table.

Referring now to the drawing 1 is the usual drum, 2 the line shaft and 3 the engine. An additional sprocket wheel 4 is mounted upon the drum shaft 5, to which it may be coupled or uncoupled as required by means of clutch member 6. This sprocket wheel is driven by means of a chain 7 by the sprocket wheel 8 mounted upon the reduction gear 9 which in its turn is driven from the line shaft 2. This reduction gear is so designed that the sprocket wheel 8 revolves more slowly than the belt pulleys 10 of the reduction gear, the gear in its turn being driven as follows:—A belt pulley 11 is mounted on the line shaft and carries two belts 12 and 13, the belt 12 being shown as crossed, which pass over a set of fixed and loose pulleys 10 mounted on the high speed shaft 21 of the

reduction gear. With the line shaft revolving in one direction by suitably moving the belts, the gear can be driven in either direction or left free with the belts on the loose pulleys. The belts are moved by shifting rod 14 operated by means of piston 15 operating in a cylinder 16. This piston is caused to move to the right depending upon the steam pressure supplied through the pipe 17 and to the left by any suitable means such as a weight 18. The pipe 17 is connected to the main engine in such a way that it is filled with steam at a pressure equal or proportional to the M. E. P. in the main engine cylinder. For this purpose it should of course be connected to both ends of the main engine cylinder or cylinders, but in practice, as drilling engines are usually run in full gear, that is, with constant cut-off, it is found that the pipe 17 may be connected to the steam chest or to any part of the steam passage between the engine and the throttle. A valve, not shown, may be placed in this pipe and partially closed so as to damp out the cyclic pressure variations from the main engine and maintain a pressure on the piston 15 proportional to the M. E. P. This pressure may be indicated to the driller by a Bourdon gauge 19 mounted in a convenient position. The dial 20 of this gauge could be marked in a suitable manner, for instance, in pounds-feet or kilogrammes-metres and could further have markings representing a safe couple for different qualities and dimensions of drill stem.

Fig. 2 shows the connections between the line shaft and drum to the well known rotary table in which the frame 28 supports the rotary table 22 which is provided with teeth 24 on the under side as indicated by the dotted lines. By rotation of the drum 1 the drill stem 26 can be raised or lowered as the case may be by means of the cable or rope 23 secured to the drill at 27. Motion is imparted to the table by means of a chain 29 which receives its motion from the line shaft 2 by means of gear wheel 30. Chain 29 rotates gear wheel 31 which rotates the gear 25 thereby imparting motion to the table and drill by the meshing of teeth 24 of the table with the gear 25.

The operation of the machine is as follows: the bit is lifted a short distance from the bottom, the rotary table drive coupling thrown in and the coupling connecting the sprocket wheel 4 to the drum shaft engaged,

the throttle of the main engine being opened until the table is running at a suitable speed. The weight 18 having been suitably chosen, the piston 15 with its attached belt shifting rod will take up a position depending upon the M. E. P. in the main engine, that is, depending upon the load on the main engine. For example, should the bit meet with an obstruction by taking too big a cut, the 10 engine will be slowed down slightly, the M. E. P. will automatically rise and the belt that turns the reduction gear which operates to work the drum in the lifting direction will be moved on to the fixed pulley. In this 15 way the bit will be automatically raised, to be automatically lowered as soon as the load on the engine decreases. Should the couple in the drill stem continue to rise in spite of the bit being lifted up, the piston 15 in its 20 extreme position to the right can be arranged to throw out the table coupling or shut off steam to the main engine.

It will be appreciated that the invention is not limited to the precise construction 25 hereinbefore described, for obviously many modifications may be made in the exact details of the mechanical construction without departing from the scope of the present invention. For instance, the above description 30 and drawing refer to the invention as applied to existing rotary machinery with only slight alterations. Should the draw-works be specially designed from the beginning, a mechanically more perfect apparatus could 35 be incorporated with them. For instance, the belts and gear might be replaced by a gear and clutches mounted directly on the line or drum shaft. According to another 40 feature of the invention the feed could be controlled by an auxiliary steam engine geared to the drum and supplied with steam at line pressure but with its power and direction of rotation controlled by a device similar to that described above for controlling 45 the position of the belts.

I claim as my invention:—

1. Drilling machinery comprising an operating engine; a line shaft rotated by said engine; a drum adapted to be operated from 50 said line shaft; a belt pulley on said line shaft; a reduction gear adapted to control said drum and having a plurality of pulleys; a plurality of belts on said belt pulley and adapted to operate the plurality of pulleys 55 of said reduction gear; and means responsive to the pressure of the operating medium of said engine for automatically shifting said belts in order to control the drum.

2. A controlling device for a drum of a 60 drilling machine comprising a reduction

gear having a plurality of pulleys thereon and adapted to drive said drum; means associated with said pulleys for driving the reduction gear; and means responsive to the pressure of the operating medium of the engine of said drilling machine for controlling the last-named means for varying the speed and direction of rotation of said drum. 65

3. A controlling device for a drum comprising a line shaft operated by an engine; a reduction gear adapted to control said drum; means for operating said reduction gear from said line shaft; a piston and cylinder for controlling said means; and means for automatically controlling said piston 75 from said engine.

4. A controlling device for a drum of a drilling machine comprising driving means driven by an engine and adapted to drive said drum; a plurality of driving belts for 80 operating the driving means; and a cylinder and piston responsive to the pressure of the operating medium of the engine of said drilling machine for shifting said belts to vary the speed and direction of rotation of said 85 drum.

5. Drilling machinery comprising an engine; a line shaft driven by said engine; a drum; a reduction gear driven by means of 90 belts from said line shaft and adapted to drive said drum; a cylinder; a piston in said cylinder operatively connected to said belts; and means for communicating the pressure of the operating medium of said engine to the cylinder in order to shift said belts by means 95 of said piston to thereby vary the speed and direction of rotation of said drum.

6. Drilling machinery comprising an operating engine; a line shaft rotated by said engine; a drum adapted to be operated from 100 said line shaft; a belt pulley on said line shaft; a reduction gear adapted to control said drum and having a plurality of pulleys; a plurality of belts on said belt pulley and adapted to operate the plurality of pulleys 105 of said reduction gear; and a piston and cylinder responsive to the pressure of the operating medium of said engine for automatically shifting said belts in order to control the drum.

7. A controlling device for a drum of a drilling machine comprising driving mechanism driven by an engine and adapted to drive said drum; and a piston and cylinder responsive to the pressure of the operating 110 medium of the engine for operating and controlling said driving mechanism.

In testimony whereof I have signed my name to this specification.

JOHN THOMSON HAYWARD.
